20 Claims. (Cl. 216—1)

It is known to purify or separate liquids, and also metal melts, by centrifuging. It has also been proposed to develop the rotational movement of the melt by the application of an electric rotary field. The use of an electric rotary field offers the advantage that the vessel containing the melt is stationary.

The present invention relates to a procedure such as the last mentioned. The object is to effect the rapid formation and the maintenance of a paraboloid of rotation even in the treatment of large volumes of material. For this purpose, according to the present invention, mechanical or electrical means are employed operating not only from outside but also inside the vessel, which conduct to the formation of a paraboloid of rotation. It contributes to the effect of the invention, when the middle space of the centrifuging vessel is occupied by a displacer, whereby the material in the vessel has a substantially annular distribution before the centrifuging begins. This achieves a concentration of the magnetic lines of force in the remaining annular space and consequently a strengthening of the eddy currents induced there, and of the resulting whirling moment. The dragging around of a mass located in the center and traversed by a field of low density is avoided. The displacer may comprise an electrical apparatus, and can thus serve to contain means to develop an inner field, or the displacer may be formed as a rotor. The action of the inner field can also be obtained without a displacer by sending electric currents directly through the melt. The melt can be considered as the rotor of an asynchronous or of a synchronous motor. In the latter case it is to be observed that the electrical synchronism need not necessarily be also a mechanical synchronism because with synchronous rotation, for example by means of a direct current supply, the melt as a liquid may lag behind the rotating pole so that at any instant another region of the melt becomes a conductor. Therefore, both direct current and alternating current can be passed through the melt. When alternating current is used, this must have the same frequency as the field if it is to be passed through the melt from points of supply which are stationary therein. Direct current, on the other hand, is passed through the melt from conductors dipping into the melt and rotating with the speed of the field, or from such a conductor in the axial direction, in such a manner as to form poles. In another modification of the invention the rotary field is

developed by mechanical regulation of a polar field.

The passing of a current through the melt constitutes the simplest manner of locating the rotary field generating means partly into the vessel. The whirling moment on the melt is thereby increased, the melt is heated by the passage of the current, and also it is possible to have automatic disconnection of the current supply in dependence upon the formation of the paraboloid of rotation. For the latter purpose, the upper current supply conductor to the melt is arranged so high and at such a distance from the axis of the vessel, that the resulting paraboloid of rotation will detach itself from the conductor upon the attainment of a predetermined rotary speed. Upon interruption of the current supply the rotational speed diminishes until the paraboloid of rotation again contacts the conductor and closes the circuit. Regulation according to the same principle can be obtained when one phase of the current used to generate the rotary field is passed over a corresponding conductor through the melt to the stator which generates the rotary field.

The purposes of electrically influencing the melt can also be served by disposing in the melt a portion of the stator which generates the rotary field, or by constituting the melt as a rotor. The formation of the rotary field by mechanically rotating a polar field has the advantage of independence from the frequency of the polyphase current, the influence of which is replaced by the controllable influence of the speed of rotation. The rotating poles may be arranged inside the vessel (in the displacer) or outside the vessel. If they are arranged both inside and outside, then they must rotate with equal speed. If in this arrangement a positive pole lies opposite a negative pole, then the arrangement constitutes the inverse of the known eddy current break. Operation is possible, however, also when similar poles lie opposite each other. The lines of force then run in the outer zones of the ring from pole to pole instead of transversely through the melt. But also in this case there is a variation of the magnetic field strength at every place in the melt owing to the rotation of the poles, so that eddy currents are induced, and the melt is carried around. These considerations also hold good for the arrangement of the polyphase induced fields which usually run synchronously, but it may be so arranged that the opposite poles are fed with similar phases or with different phases. Three modifications according to the invention are illus-

trated diagrammatically in the drawing, in which:

Figure 1 is a vertical sectional view showing the first arrangement.

5 Fig. 2 is a similar view of the second modification, and

Fig. 3 is a horizontal section through the apparatus of Fig. 2, the electrical equipment and its arrangement being shown diagrammatically.

10 In the drawing, 1 designates the stationary nonmetallic centrifuging vessel for containing the melt, supplied through a chute 2. A stator 3 energized by polyphase current, surrounds the vessel. Owing to the action of the rotary field, 15 the melt is set in rotation and forms a paraboloid of rotation 4. The chute 2 is so formed and arranged that it meets the inner surface of the paraboloid approximately tangentially in the direction of rotation.

20 The specifically lighter constituents collect at the inner surfaces of the paraboloid. The speed of rotation is so regulated that the inner surface intersects the discharge orifice 5 through which the specifically lighter constituents, for 25 example impurities, flow off.

The heavy constituent, for example the purified iron, is led off at the outer periphery, for example, through the outlet pipe 6. The arrangement shown in Fig. 1 therefore permits uninterrupted operation, unpurified cast iron, for example, being continuously supplied, and slag and purified iron being continuously discharged at separate points.

If the walls of the centrifuging vessel are inclined, the heaviest constituents move upwardly where they can be removed at the place most remote from the axis of rotation. Means for removal of such constituents may therefore also be furnished at this place or at any selected point.

35 40 In the arrangement shown in Fig. 1, 7 designates the supply conductor to the melt, this conductor terminating in a terminal 8 which is preferably streamlined. The conductor 7 is insulated by a refractory sleeve 9. The conductor 7 and terminal 8 may be hollow and water cooled, they may consist of the same material as the melt. Similar considerations apply to the second conductor 10 ending in a terminal 11 arranged above the terminal 8. The current flows between the 45 terminals 8 and 11, transversing the outer region of the melt. At the diametrically opposite side it can be conveyed back in the reverse direction. The inner surface of the paraboloid of rotation assumes such a position that it touches the terminal 11.

50 In the modification shown in Fig. 2 the center space of the centrifuging vessel is occupied by a hollow displacer 14 inside which a second rotary field generator 13 is disposed. The rotary field generator 3 and 13 may be replaced by driven 55 rings of magnetic poles.

In Fig. 3 the external and internal rotary field generators are each shown as having one pole for each of the phases I, II, III. The external 60 rotary field generator is in star connection and the internal rotary field generator is in mesh connection.

The internal stationary or driven rotary field generator 13 with its container 14 may be replaced by a rotor driven by the external rotary field. This rotor is sheathed with a refractory and heat insulating jacket wholly or partly enclosing it. The jacket is preferably provided with ribs extending into the melt to improve the 65 drive of the melt by the rotor. The rotor does

not have to be mounted in fixed bearings but can float in the melt. In the limiting case it may consist substantially of a magnetizable iron core sufficiently protected against the action of the melt. The rotor may be annular. It may also be used merely as an electric whirling device for mixing metal melts. Also a stationary central displacer can be used containing an iron core to improve the magnetic flux.

5 We claim as our invention:

10 1. A process for purifying and separating electrically conducting liquids which are not decomposed under the influence of electricity, comprising whirling the conducting liquid in a stationary vessel by the application to said liquid 15 of a rotary magnetic field, and removing constituents of different specific gravity from parts of the paraboloid of revolution formed by the whirling liquid, at different distances from the axis of rotation.

20 2. A process for purifying and separating electrically conducting fluids which are not decomposed under the influence of electricity, comprising rotating the fluid by a magnetic field and removing constituents of different specific gravity, 25 from various parts of the rotating fluid.

30 3. A process according to claim 1, in which the step is included of continuously supplying fresh liquid tangentially at the inner surface of the paraboloid and continuously removing the separated constituents.

35 4. A process according to claim 1, in which the rotary magnetic field is generated from the outside and from the inside of the stationary vessel.

40 5. A process according to claim 1, in which the liquid is displaced from the middle of the container prior to the formation of the paraboloid of revolution.

6. A process according to claim 1, in which the rotary field is generated by direct current fed into the liquid at a terminal or terminals rotating at the same speed as the rotary field.

45 7. A process according to claim 1, in which the rotary field is generated by mechanically rotating a polar field.

8. A process according to claim 1, in which the rotary field is generated by a polyphase current.

9. A process according to claim 1, in which the speed of whirling is regulated by causing the periphery of the paraboloid of revolution to act as a contact in the electric circuit supplying the current which produces the rotation.

55 10. Apparatus for purifying and separating electrically conducting liquids which are not decomposed under the influence of electricity, comprising a stationary vessel for the liquid, means for whirling the liquid in the vessel by the action of a rotary magnetic field, and means for withdrawing parts of the liquid from certain parts of the whirling liquid.

60 11. Apparatus for purifying and separating electrically conducting liquids which are not decomposed under the influence of electricity, comprising a stationary vessel for the liquid, means for whirling the liquid in the vessel by the action of a rotary magnetic field, an outlet for lower specific gravity constituents, and an outlet for higher specific gravity constituents, said outlets 65 communicating with parts of the paraboloid of revolution formed by the whirling liquid, at different distances from the axis of rotation.

70 12. Apparatus according to claim 11, in which a chute is provided for supplying fresh liquid into 75

the vessel arranged to deliver tangentially to the inner surface of the paraboloid.

13. Apparatus according to claim 11, in which a displacer is provided in the center portion of the vessel.

14. Apparatus according to claim 11, in which the means for producing a rotary magnetic field capable of whirling the liquid are provided both externally and internally of the vessel.

10 15. Apparatus according to claim 11, in which the means for producing a rotary magnetic field capable of whirling the liquid are provided both externally and internally of the vessel, and in which a displacer is provided in which the internal field producing means is placed.

15 16. Apparatus according to claim 11, in which the means for producing a rotary magnetic field capable of whirling the liquid are provided both externally and internally of the vessel, and in which a displacer is provided in which the internal field producing means is placed, said displacer being in the form of a rotor.

20 17. Apparatus according to claim 11, in which the means for producing a rotary magnetic field capable of whirling the liquid are provided both externally and internally of the vessel, and in

which a displacer is provided in which the internal field producing means is placed, said displacer being in the form of a rotor having ribs on the outer surface to assist the whirl of the liquid.

5 18. Apparatus according to claim 11, in which the means for producing a rotary magnetic field capable of whirling the liquid are provided both externally and internally of the vessel, and in which a displacer is provided in which the internal field producing means is placed, said displacer being in the form of a rotor which floats in the liquid.

10 19. Apparatus according to claim 11, in which the means for producing a rotary magnetic field capable of whirling the liquid are provided both externally and internally of the vessel, and in which terminals are provided in the liquid.

15 20. Apparatus according to claim 11, in which one of the outlets is provided adjacent the axis 20 of the vessel for the lower specific gravity constituents and the other outlet for the higher specific gravity constituents is near the periphery of the vessel.
